UNITED STATES PATENT OFFICE.

JEAN REY, OF PARIS, FRANCE.

TIME APPARATUS FOR USE WITH SUBMARINE MINES.

1,358,466.

Specification of Letters Patent.

Patented Nov. 9, 1920.

Application filed April 25, 1918. Serial No. 230,849.

To all whom it may concern:

Be it known that I, JEAN REY, a citizen of the Republic of France, and a resident of Paris, France, engineer, have invented 5 a new and useful Improvement in Time Apparatus for Use with Submarine Mines, which invention is fully set forth in the following specification.

This invention relates to improved time 10 apparatus for those submarine mines which when released by the submarine boat carrying them fall together with their anchor to the bottom of the sea.

The time apparatus in accordance with 15 this invention has for its object to liberate the mine from its anchor at the moment required and to allow its mooring rope to unwind, the time apparatus is automatically released directly the mine leaves the submarine 20 by the movement of a cock or a bolt, the breaking of a member or in any other known way.

Three methods of carrying out the invention are illustrated in the accompanying 25 diagrammatic drawing in cases where the mine is fixed to the side of the submarine boat.

In Figure 1, the control is effected by the aid of a projection fixed to the submarine 30 boat.

In Fig. 2 the control is effected by the aid of a cock.

In Fig. 3, the release is effected by the breakage of an immobilizing member.

35 Figs. 4, 5 and 6 are diagrammatic views showing other constructional forms of means for releasing the timing device.

Fig. 1 shows the mine *a* on its anchor *b*; the attaching arrangement is illustrated 40 diagrammatically in the form of hooks *c*. The assembled mine and anchor are retained near to the submarine boat by any known means not illustrated. A time apparatus illustrated diagrammatically in the form of 45 a dash-pot *e* the piston of which is forced to the right by a spring *f* is maintained stationary by a projection *g* carried by the submarine boat.

The time apparatus *e* becomes separated 50 from the projection *g* when, at the moment of launching, the mine is detached from the submarine boat to fall to the bottom of the sea; it is now free to move. After a certain interval dependent on construction 55 the hooks *c* are moved the extent necessary to free the mine from its anchor *b*.

In Fig. 2 the opening of a cock *h* brings into action the time apparatus *e*. A projection *g* carried by the submarine boat, knocks the tail of the cock *h* and opens 60 it when, on launching, the mine becomes detached from the submarine boat to fall to the bottom of the sea.

In order better to regulate the path of travel of the cock *h* near to the projection 65 *g*, a guide *i* may be provided to guide the mine with reference to the submarine boat.

The cock *h* when open allows the time apparatus *e* to operate. After a certain interval it actuates the hooks *c* as in Fig. 1. 70

Of course, in place of actuating a cock, the projection *g* may lift a pin *h* as shown in Fig. 4; or operate a bolt *i*, through an immobilizing arm as in Fig. 5; or break an immobilizing member *n* at *m* as in Fig. 75 6, or cause any other operation which brings into action a time apparatus of any type even other than those illustrated.

In Fig. 3 the projection is replaced by a fixed point *k* which brings into action the 80 time apparatus *e* through the intermediary of a cable *l* when, on launching, the mine becomes detached from the submarine to fall to the bottom of the sea.

The pull of the cable *l* causes the immobilizing member *n* to break at *m*. The time apparatus *e*, a certain time after being thus liberated, actuates the hooks *c* as described for Fig. 1. 85

When the mine has been thus liberated, it 90 rises to a certain level below the sea surface and is then arrested by known mechanism and maintained at the degree of immersion desired.

Claims—

1. In a combination, a submarine mine 95 provided with a separable anchor having a mooring rope-connection with said mine and adapted to be supported from the side of a boat, releasable connections between the mine and anchor, spring-pressed means normally tending to move said connections into releasing position and timing means set into operation by launching the mine for delaying the operation of said spring-pressed 100 release operating means to delay release of the mine from its anchor. 105

2. In combination, a submarine mine provided with a detachable anchor having a mooring-rope connection with said mine and 110 adapted to be supported from the side of a submarine boat, releasable catch means

normally connecting said mine and anchor, a spring-pressed catch releasing rod normally restrained from action while the mine and anchor are in supported position by the boat, and timing means automatically set in operation by launching the mine to delay the operation of said catch releasing rod

to release the mine and anchor and to permit the mooring rope to unwind.

In testimony whereof I have signed this 10 specification.

JEAN REY.
